UNITED STATES PATENT OFFICE.

CHARLES C. JESSEN, OF WILMINGTON, DELAWARE, ASSIGNOR TO ATLAS POWDER COMPANY, OF WILMINGTON, DELAWARE, A CORPORATION OF DELAWARE.

SKEINING MACHINE.

Application filed February 5, 1925. Serial No. 7,070.

To all whom it may concern:

Be it known that CHARLES C. JESSEN, a citizen of the United States, residing at Wilmington, in the county of New Castle 5 and State of Delaware, has invented certain new and useful Improvements in Skeining Machines, of which the following is a specification.

This invention relates to a skeining machine adapted to wind threads and strands in skein form upon swifts. The primary object of the invention is to provide a machine of this character comprising a multiplicity of units all driven from a common 15 drive shaft but each being arranged to be cut out of operation without affecting any of the other units and to effect this through a medium of mechanism of marked simplicity and economy of construction.

Further objects and advantages of the invention will be set forth in the detailed description which follows:

In the accompanying drawings,

Figure 1 is a plan view of a part of a skeining machine constructed in accordance with the invention with certain of the parts broken away and others omitted to preserve the clearness of the drawing.

Figure 2 is a side elevation of the structure of Fig. 1.

Figure 3 is an end elevation, and

Figure 4 is a detailed sectional view through a portion of one of the units.

Like numerals designate corresponding 35 parts in all of the figures of the drawings:

The skeining machine of the present invention comprises a base frame 5, which may be of any desired length and may support any desired number of skeining units.

Each unit comprises a transverse shaft 6, carrying a friction disc 7 at its inner end and a swift 8 at its outer end. These swifts are of a known construction, each comprising a plurality of radial, bowed wire arms 9. There are, preferably, four of these arms to each swift, two of the opposed arms being carried by hub like blocks 10 and 11 and the arms at right angles thereto being carried by hub like blocks 12 and 13. Upon the completion of the operation of winding the skeins of thread, of any character, upon the swifts, they may be collapsed to permit of the ready removal of the skeins by moving 50 one of the pairs of arms toward the other

pair of arms, in a manner common in the art.

The shafts 6 are mounted in bearing brackets 15 and carry bevel pinions 16, said pinions being splined upon said shafts by feather keys 17. The shafts 6 are further provided with collars 18 and springs 19 bear between these collars and loose collars 20. Thus the springs 19 tend to move the shafts 6 inwardly to bring their friction discs 7 into contact with driving friction discs 21 upon a main drive shaft 22 to which motion may be imparted by a belt or otherwise. To provide for the application of power to the shaft 22 a pulley 23 is mounted upon said shaft. Thus it is manifest that rotation of the shaft 22 will impart rotation to the several shafts 6 and to the swifts carried thereby, through the medium of the friction discs 21 and 7, if said discs are in contact with each other. The action of the springs 19 tends to maintain the discs 7 in driving contact with the discs 21.

The beveled pinions 16 mesh with beveled pinions 24 of slightly larger diameter, the latter being mounted upon shafts 25, journaled at one end in the bearings 15 and at their ends in bearing brackets 26. The shafts 25 carry crank discs 27 and these crank discs in turn carry wrist pins 28 that are movable in guideways 29, of slide blocks 30. The blocks 30 are carried by sliding traverse rods 31, and these rods in turn carry guides 32 over which the thread is passed on its way to the swifts. Thus as a swift is rotated to wind the threads thereon by the action of the shaft 6 the traverse arm is caused to move back and forth across the face of the swift and to wind the thread thereon in the usual and desired diamond formation.

When a swift has received the amount of thread constituting a full skein and it becomes necessary to remove said skein from the swift, the swift may be brought to rest without stopping any of the other units of the machine by the operator pulling outwardly upon a handle 33 associated with the operating mechanism of the swift. Each of the handles constitutes an extension of a vertical arm 34 that is pivoted at 35. These arms carry thrust blocks 36 that are pivoted to the arms 34. When the handle 33 of any

swift is drawn outwardly the corresponding thrust block 36 is forced against the inner face of the disc 7 and said disc is forced out of contact with the corresponding driving disc 21. The contact of the thrust block 36 with the disc 7 not only thrusts the disc out of engagement with the disc 21 but said thrust block acts as a braking element to bring the swift quickly to rest. It is manifest that the movement of the handle 33 results in moving the shaft endwise and against the tension of the spring 19. This action may take place without affecting the engagement of the gears 16 and 24 because the gears 16 are splined upon their respective shafts.

Supporting standards 38 disposed at intervals in the length of the frame 5, carry a longitudinally extending bar 39. Blocks 40 having spring arms 41 project from bar 5 and receive cylinders indicated at 42, upon which cylinders the thread is wound, when brought to the machine preparatory to winding the same into skein form. These cylinders are slipped upon the blocks 40 and are held there by frictional action of the springs 41. The thread is led from the cylinders, over guides 43, which project in opposite directions from the bar 39 and thence to the guides of the traverse arms and to the swifts.

From the foregoing it will be seen that a skeining machine is herein provided, constructed in such manner that a single operator may take care of a plurality of swifts and that such operator may stop any of the swifts, at will, either for the purpose of removing the skeins or for purposes of repair, without interfering with any of the other swifts.

It will further be seen that the mechanism for effecting the operation of all of these swifts from a common drive shaft is of a very simple and inexpensive nature.

It is to be understood that the invention is not limited to the particular embodiment herein shown and described, but that it includes within its purview whatever changes fairly come within either the terms or the spirit of the appended claims.

Having described my invention, what I claim is:

1. A machine of the character described, comprising a longitudinally extending main drive shaft, a plurality of swift carrying shafts extending in opposite directions therefrom, friction discs upon the inner ends of said swift carrying shafts, friction discs upon the main drive shaft, with which the first named friction discs engage, spring means upon the swift carrying shafts, tend-

ing to move the said shafts to bring their discs into engagement with the discs of the main drive shaft, pivoted manually operable levers which extend across the faces of the discs of the swift carrying shafts, and brake elements carried by said levers and bearing upon the friction discs of the swift carrying shafts and handle extensions upon said levers projecting outwardly toward the swifts, movement of said levers shifting said discs out of engagement with the discs of the main drive shaft and applying a brake thereto.

2. A machine of the character described comprising a longitudinally extending main drive shaft, a plurality of swift carrying shafts extending in opposite directions therefrom, friction discs upon the inner ends of said swift carrying shafts, friction discs upon the main drive shaft with which the first named friction disks engage, spring means upon the swift carrying shafts tending to move the said shafts longitudinally to bring their discs into engagement with the discs of the main drive shaft, beveled pinions sliding upon the swift carrying shafts, beveled pinions meshing with the first named pinions, shafts upon which the beveled pinions are mounted, cranks and wrist pins upon the ends of said shafts, sliding blocks with which said wrist pins are engaged, and traverse rods by which the sliding blocks are carried.

3. A machine of the character described comprising an elongated main frame, a longitudinally extending main drive shaft thereon, a plurality of horizontally disposed swift carrying shafts, extending laterally in opposite directions with respect to the main drive shaft, individual friction drive mechanisms between the main shaft and each of the said swift carrying shafts, comprising interengaging friction discs upon the main shaft and the swift carrying shafts, respectively, an individual, manually operable controlling member for each swift carrying shaft, each of said controlling members comprising a horizontal portion and a vertical portion, the horizontal portions of said members extending outwardly and terminating in handles above the swifts and the vertical portions extending downwardly across the faces of the discs of the swift carrying shafts and being pivoted below the level of said discs, and thrust blocks constituting braking elements pivoted upon said vertical portions and bearing against the inner faces of the discs of the swift carrying shafts.

In testimony whereof he affixes signature.

CHARLES C. JESSEN.
